United States Patent Office.

SANFORD BECKWITH, OF OSHKOSH, WISCONSIN.

Letters Patent No. 79,189, dated June 23, 1868.

IMPROVEMENT IN SEEDING-MACHINE.

The Schedule referred to in these Letters Patent and making part of the same.

TO ALL WHOM IT MAY CONCERN:

Be it known that I, SANFORD BECKWITH, of the city of Oshkosh, county of Winnebago, and State of Wisconsin, have invented a new and improved Seeding-Machine; and I do hereby declare that the following is a full and exact description thereof, reference being had to the accompanying drawings, and to the letters of reference marked thereon, the same making a part of these specifications, in which—

Figure 1 is a perspective view.

Figure 2 is a vertical section.

Figure 3 is a fragment of a longitudinal section.

Figure 4 is a perspective view of the cup m ; m' is a vertical section of fig. 4; r is a bearing for the shaft r' , figs. 2 and 5.

Figure 5 is a perspective view of the screw-cylinder d ; f' is an end view, showing the terminal shape of the screw-threads at f .

Figure 6 is a front elevation of the back or part l of the scattering-tubes.

Figure 7 is a front elevation of the front or part k of the scattering-tubes; $l' k'$ is a vertical section of the top, $l'' k''$ a vertical section of the centre, and $l''' k'''$ a vertical section of the bottom of the scattering-tube $l k$, seen also in figs. 2 and 3; $n n$, fig. 6, are slots that admit of a vertical adjustment of l relative to k ; $n' n'$, in k , are ears with bolt-holes for securing l and k to the axle a , as seen in figs. 2 and 3; t , in fig. 6, is a half conical shape; the bottom horizontal shape may be seen at l''' ; the vertical shape may be seen at l , figs. 2 and 3.

Figure 8 is a fragmental view in perspective of a series of adjustable caps or cut-offs, seen in fig. 1, and at e in figs. 2 and 3; $i i$ is a longitudinal sliding frame; $r'' r''$ are supports permanently secured to the bottom edge of the seed-box, and hold the sliding frame to service.

Figure 9 is an enlarged view of the lag and cultivator-tooth, seen in fig. 2, with mode of adjusting and securing the tooth relative to the lag; q is a rod or metallic connection between tooth o and lag p ; S is a hook-bolt, and is the medium through which the tooth o is secured and adjusted to the rod q . E' is a view of the hook-bolt attached to a fragment of tooth o . The outer third of the rod q is bent to a circular form, corresponding with the radius described, from its connection with the lag p by the tooth o ; a is an axle; $c c$ is a horizontal frame; b is a seed-box; b' is a hopper to seed-box.

The purpose of this invention is to provide a more uniform, reliable, and efficient means of feeding the grain to the scatterer, or to a drill-delivery, and to provide a scatterer that is adjustable, and that may be equally well adapted to either wheat or oats.

The novelty of this invention consists in the employment and adaptation of certain devices and their use jointly, and in combination with the seed-box, shaft, and other auxiliaries of a seeding-machine. The shaft has its bearings on a framework attached to the axle beneath the seed-box. On the shaft at proper intervals, is provided a series of screw-cylinder seed-distributors, revolving with the shaft. The screw of the cylinder may be double or single, and of any practical form known to the art, or of the particular form represented in the drawings. In the latter form, the space between threads at one end of the cylinder is of a minimum size, both as to width and depth, and gradually increases in size both as to width and depth, until the thread or threads worm the whole length of the cylinder. The ends of the threads are rounded from the outer periphery of the cylinder to the bottom of the space between threads.

Each cylinder is provided with a cup, of a half cylindrical form, or it may be of any other form known to the art, wherein the seed-cylinders rotate. The difference in size between the diameter of the cylinder and the inner periphery of the cup is sufficient to obviate any possible chance of crushing or bruising the seed when the cylinders are revolving. The discharge-end of the cup may be of any convenient form known to the art, that will admit a discharge of the grain, or may be as represented in the drawings, wherein the cup is notched and the ends partially moulded in towards the radial centre, in such a form relative to the discharge-end of the screw-cylinder, that when the cylinder is in motion, a continuous and uniform discharge of the grain will be

effected. Over each cylinder are located adjustable semicircular caps or cut-offs, which, together with the cups, encircle the cylinders. The caps are each secured to a parallel frame, which in turn is held to service by slide-bearings secured to the bottom of the seed-box. The parallel frame and the caps are made to slide, and are designed both to cut off entirely the flow of grain, and are adjustable to regulate the quantity of grain sown to a given area. It will be noted that by reason of the gradual increase of the space between the screw-threads in the cylinder, and as you adjust or increase the opening of the cap or cut-off relative to the cylinder, in proportion you increase the discharge of the grain as to quantity. It may be remarked further, that the scattering of grain is uniform over the area travelled, whether the machine be driven quickly or moderately.

Beneath the seed-distributing cylinders and cups is arranged a series of tubes or scatterers, of a semi-elliptical form (horizontally.) The lower half of the inner or adjustable part is primarily flat, but has a conical form, with a half-elliptical-shaped flange at the bottom, and a flaring or hopper-shape at the top. The outer or stationary part, while it is of a semi-elliptical form (horizontally,) is largest at the top, and thus, in conjunction with the part first described, forms a hopper. It is smallest in the centre, and of a medium size at the bottom, sufficient in size, however, to leave ample space between the outer and stationary part and the inner or adjustable part for the discharge and scattering of the grain.

The inner part is provided centrally with slotted openings, that allow of a vertical adjustment, and thus provides for an adjustment of the discharge that adapts the tubes to scatter equally well, over the same area, wheat and oats.

The cultivator-tooth is pivoted at one end of the lag. Dropping diagonally from the lag is a metallic rod or brace, the outer end being bent to a circular form, to allow an adjustment of the tooth. The circular part of the brace intersects the tooth to which the same is secured by a hook-bolt; the hook clasping the brace, holding it firmly to the tooth, and is thus secured by a nut on the opposite side of the tooth. By loosening the nut and sliding the tooth, it may be adjusted to any required angle.

What I claim as my invention, and desire to secure by Letters Patent, is—

1. The screw-cylinder *d*, cup *m*, and adjustable cap *e*, arranged relatively one to the other for joint action, substantially as and for the purposes set forth.
2. The screw-cylinder *d* in combination with cup *m*, as herein described for the purposes set forth.
3. The semi-elliptical tube or scatterer *k l*, as and for the purposes set forth.
4. The slots *n n*, as a means of adjusting the part *l* relative to the part *k*, as and for the purposes set forth.

SANFORD BECKWITH.
